CLAIM

The ornamental design for a thin wall pack light fixture as shown and described.

DESCRIPTION

FIG. 1 is a front top perspective view of a first embodiment of the thin wall pack light fixture;

FIG. 2 is a front bottom perspective view thereof;

FIG. 3 is a front view thereof;

FIG. 4 is a back view thereof;

FIG. 5 is a left side view thereof;

FIG. 6 is a right side view thereof; and

FIG. 7 is a top view thereof;

FIG. 8 is a bottom view thereof;

FIG. 9 is an enlarged view of portion "9" shown in FIG. 8;

FIG. 10 is a sectional view taken from the sectioning plane labeled "10" shown in FIG. 3;

FIG. 11 is a front top perspective view of a second embodiment of the thin wall pack light fixture;

FIG. 12 is a front bottom perspective view thereof;

FIG. 13 is a front view thereof;

FIG. 14 is a back view thereof;

FIG. 15 is a left side view thereof;

FIG. 16 is a right side view thereof; and

FIG. 17 is a top view thereof;

FIG. 18 is a bottom view thereof;

FIG. 19 is an enlarged view of portion "19" shown FIG. 18;

FIG. 20 is a sectional view taken from the sectioning plane labeled "20" shown in FIG. 13;

FIG. 21 is a front top perspective view of a third embodiment of the thin wall pack light fixture;

FIG. 22 is a front bottom perspective view thereof;

FIG. 23 is a front view thereof;

FIG. 24 is a back view thereof;

FIG. 25 is a left side view thereof;

FIG. 26 is a right side view thereof; and

(Continued)

FIG. 27 is a top view thereof;
 FIG. 28 is a bottom view thereof;
 FIG. 29 is an enlarged view of portion “29” shown in FIG. 28;
 FIG. 30 is a sectional view taken from the sectioning plane labeled “30” shown in FIG. 23;
 FIG. 31 is a front top perspective view of a fourth embodiment of the thin wall pack light fixture;
 FIG. 32 is a front bottom perspective view thereof;
 FIG. 33 is a front view thereof;
 FIG. 34 is a back view thereof;
 FIG. 35 is a left side view thereof;
 FIG. 36 is a right side view thereof; and
 FIG. 37 is a top view thereof;
 FIG. 38 is a bottom view thereof;
 FIG. 39 is an enlarged view of portion “39” shown in FIG. 38; and,
 FIG. 40 is a sectional view taken from the sectioning plane labeled “40” shown in FIG. 33.

The evenly-spaced broken lines in the figures illustrate portions of the article that form no part of the claimed design. The dot-dash broken lines in the figures illustrate a symbolic break and enlarged view boundaries that form no part of the claimed design. FIGS. 1-4 and 7-8 are shown with a symbolic break line and a brace symbol along the dimensional length of the article. The appearance of any portion of the article between the break lines forms no part of the claimed design.
